(57) **CLAIM**

The ornamental design for a robotic toy caterpillar, as shown and described.

DESCRIPTION

FIG. 1 is a top perspective view showing a first embodiment of the robotic toy caterpillar;

FIG. 2 is a top side view of FIG. 1;

FIG. 3 is a bottom side view of FIG. 1;

FIG. 4 is a front side view of FIG. 1;

FIG. 5 is a back side view of FIG. 1;

FIG. 6 is a left side view of FIG. 1;

FIG. 7 is a right side view of FIG. 1;

FIG. 8 is a bottom perspective view of FIG. 1 with sectional line 9; and,

FIG. 9 is a cross sectional view of FIG. 8 across sectional line 9.

The broken lines are for the purpose of illustrating portions of the environmental structure and forms no part of the claimed embodiment and design.
